DESK LAMP

Jacob A. Mehr, Kirkwood, Mo., assignor to Dazor Manufacturing Corp., St. Louis, Mo., a corporation of Delaware

Application October 11, 1956, Serial No. 43,323

Term of patent 3½ years

(Cl. D48—19)

FIG. 2.

Fig. 1 is a top plan view of a desk lamp, showing my new design, and

Fig. 2 is a perspective view thereof.

I claim:

The ornamental design for a desk lamp, substantially as shown.
